REFRIGERATOR CABINET

Albert P. Ball, Detroit, Mich., assignor to Briggs Manufacturing Company, Detroit, Mich., a corporation of Michigan

Application October 26, 1931, Serial No. 571,245

3 Claims. (Cl. 220—9)

This invention relates to refrigerator cabinets and more particularly to a novel construction thereof tending to simplify, render the same more efficient and improve the same generally.

5 In accordance with this invention, I propose a construction wherein the usual or customary frame members of the cabinet are eliminated, the body of the cabinet being composed of or built up from form-sustaining panels or sheets of insulating material interfitted and secured together to form all of the walls of the cabinet. The inner and outer metal panels are then associated with this structure to produce the finished cabinet.

10 One notable advantage of a construction of this character is the simplicity of the structure which enables it to be manufactured and assembled not only quickly, but economically. Another advantage obtained is an increased efficiency in the cabinet resulting from the adequate heat insulating properties of the structure in which the insulating panels extend throughout the walls and are secured directly to one another without the interpositioning of frame members of other materials.

15 25 The several objects, advantages and novel details of construction of the invention will be made more apparent as this description proceeds, especially when considered in connection with the accompanying drawings, wherein

30 Figure 1 is a vertical sectional view through a refrigerator cabinet constructed in accordance with this invention;

35 Figure 2 is a horizontal sectional view through the cabinet taken substantially on the plane indicated by line 2—2 in Figure 1;

Figure 3 is a perspective view of the body of the cabinet formed of the panels of insulating material as seen from the rear; and

40 Figure 4 is a similar view as seen from the front.

Referring now more particularly to the drawings wherein like reference characters indicate like parts, it will be noted that the body of the refrigerator is composed of sheets or panels of form-sustaining insulating material assembled to produce the side walls 10, back wall 11, bottom 12 and top wall 13 of the cabinet. As shown probably best in Figure 2, the rear vertical edges of the side walls 10 are formed with rabbets 14 with which the vertical edges of the rear wall 11 engage, these walls being united by dowels 15 passed through the rabbeted portions of the side walls and into the vertical edges of the rear wall 11.

55 As seen in Figure 1, the rear edge of the bottom

12 is formed with a rabbet 16 with which the lower edge of the rear wall 11 engages, dowel pins 17 being provided for securing these wall members together.

As seen in Figure 1, the top wall 13 extends from the front of the cabinet to a point spaced forwardly of the rear side of the cabinet to provide a space 18 for the purpose, for instance, of receiving a mechanical refrigerator unit (not shown).

The complementary top wall portion 13' which 10 constitutes the bottom wall of this space 18, is provided with a rabbet 19 to receive the upper edge of the rear wall 11, dowels 20 being provided for securing these wall members together. As 15 probably best seen by a comparison of Figures 1, 3 and 4 the side walls 10 extend upwardly above the top wall 13, these upward extensions being indicated by the reference character 10' and also these walls extend to the rear side of the cabinet as shown in Figure 1 and constitute the side 20 walls of the unit-receiving space or compartment 18.

The end faces of the wall section 13 abut the opposed faces of the side walls 10, dowels 21 being provided for securing the wall section 13 to 25 the side walls. In a like manner the end faces of the wall section 13' are secured to the side walls by dowels 22.

The upper rear corners of the side walls 10 are recessed as at 23 to receive a transversely extending frame member 24 to which the outer metal panel of the cabinet, yet to be referred to, is secured.

The side edges of the bottom 12 are provided with rabbets similar to the rabbet 16 at the rear 35 edge of the bottom, to receive the lower edges of the side walls 10, dowels similar to the dowels 17 also being employed for securing the bottom and side walls together.

The forward edge of the top panel 13 is formed 40 with an inclined face 25 and the forward edge of the bottom 12 is provided with an inclined face 26, corresponding inclined faces 27 being formed on the forward edges of the side walls 10, these inclined faces constituting the face of the 45 door opening with which the door 27, engages.

The opening defined by the side walls 10 and the vertically aligned edges of the walls sections 13 and 13', is provided with a frame 28 to which the refrigerator unit (not shown) is attached.

50 From the description thus far it will be seen that the body of the refrigerator cabinet is built up of sheets or panels of insulating material connected together by tightly fitting joints so as to produce a substantially complete cabi- 55

net structure formed practically entirely of insulating material.

No framing is required and hence the insulating material extends throughout the walls of the cabinet.

The body of insulating material when thus constructed is next sheathed or enclosed by the inner and outer metal panels 29 and 30 of the cabinet. The joint between the inner and outer panels at the door opening is covered by a finish strip frame member 31 with which there may be associated, if desired, an inner sealing member 32 providing a seal between the door opening and the inner periphery of the door 27. The door 27 is composed of a panel of insulating material 33 enclosed within metal panels 34 and 35, the door being provided at its outer periphery with a sealing strip 36 forming a second seal between the door and the door opening of the cabinet.

The unit-receiving space 18 is enclosed by rear metal panel 37 and a top panel 38.

The metal panels fit the panels comprising the body of the cabinet snugly and as a consequence impart rigidity thereto and to the cabinet structure in its entirety.

In describing this invention no particular type of insulating material has been referred to because obviously, various types may be used, the only requisite being that the insulating material be of such a nature that it may be made in form-sustaining sheets or panels. Moreover, the particular manner in which the inner and outer metallic panels of the cabinet are united, is of little or no consequence insofar as this invention is concerned, because the invention consists generally in the construction of the body of the box entirely of insulating material which is subsequently sheathed or enclosed in the metallic inner and outer panels of the cabinet.

What I claim as my invention is:

1. A refrigerator cabinet comprising a self-

sustaining walled cabinet structure of insulating material, said walled structure comprising a plurality of relatively rigid unitary sections, each section comprising a single piece of insulating material arranged to form an enclosing wall of the structure, said sections having their adjacent edges lapped in abutting relation and directly joined together without reinforcing frame members to provide a self-sustaining walled structure consisting of the sections thus joined together, and metal sheathing preformed to fit the outer and inner surfaces of the walled structure and concealing the junctures of the sections.

2. A refrigerator cabinet comprising a self-sustaining walled cabinet structure of insulating material, said walled structure comprising a plurality of relatively rigid unitary sections, each section comprising a single piece of insulating material arranged to form an enclosing wall of the structure, said sections having their adjacent edges interfitting in abutting relation and directly fastened together without a supporting framework to provide a self-sustaining walled structure consisting of the sections thus fastened together, and metal sheathing preformed to enclose said walls and covering the points of fastening of the sections.

3. A refrigerator cabinet comprising a self-sustaining walled cabinet structure of insulating material, said walled structure comprising a plurality of relatively rigid one-piece sections, each formed from a single piece of insulating material and arranged to form an enclosing wall of the structure, said sections having their adjacent edges lapped in abutting relation, means for joining said lapped edges together to provide a self-sustaining walled structure of insulating material without supplemental supporting means for the sections, and metal panelling angularly formed to cover said sections, the junctures thereof and said joining means.

ALBERT P. BALL.
